UNITED STATES PATENT OFFICE.

ROBERT C. ANGELL, OF PRINCE BAY, NEW YORK, ASSIGNOR TO THE S. S. WHITE
DENTAL MANUFACTURING COMPANY, A CORPORATION OF PENNSYLVANIA.

STRAND TWISTING AND COILING MECHANISM.

Application filed August 7, 1924. Serial No. 730,740.

REISSUED

My invention relates particularly to that class of mechanism or machines that are adapted to produce cables or ropes formed of a plurality of strands twisted or wound together, and is especially directed to mechanism wherein a plurality of strands of wire are helically coiled around a mandrel or stranded core to form a cable which may be employed as a driving shaft for connecting movable elements for synchronous actuation.

In the production of flexible cable or shaft formed of a plurality of layers of wire or strip material superposed in coiled relation one upon the other, there are considerable stresses inherent in the fabricated product, due to the tension effected by bending of the individual strands in coiling them about the mandrel, which tends to produce torsional stress, and which effects undue internal friction when such cable is rotated about its axis in flexed or curved condition, and furthermore, there is a tendency of this fabricated product when released to recoil and thereby twist upon itself into a tangled mass. Owing to the inherent stresses effected by the tension of the individual strands of such cable it has heretofore been impractical to produce cable which is sufficiently free from internal friction as to be successfully employed as a driving shaft, except in such limited lengths as to require the constant attention of an attendant.

The principal object of my invention is to provide in flexible cable or shaft producing mechanism, means tending to so twist the fabricated cable or shaft as to relieve the inherent stresses incident to the tension effected by the laying on of the strands of the superposed windings, whereby such inert flexible shaft, or shaft substantially free from internal friction and embodying the desired flexibility, may be produced in what may be termed continuous length, or shaft that may be taken up by spooling mechanism as fabricated.

Other objects of my invention are to provide means arranged to twist the mandrel or core upon which the superimposed strands are being laid to form a composite or fabricated cable, and to provide means to so twist said fabricated cable thus produced, as to effect a slight recoil or turning back of the coiled strands and thereby so relieve the stresses inherent therein as to render the fabricated cable inert, or substantially free from

internal friction when employed as a driving or connecting shaft and rotated, or otherwise actuated, in flexed or curved condition.

Specifically stated the form of my invention, as hereinafter described, comprises a core spool carrier or payout mechanism, a strand bobbin carrier or winding mechanism, and recoil or untwisting mechanism, all rotatable about the longitudinal axis of the fabricated cable, and a take-up reel or spooling mechanism, which may or may not be arranged to rotate about said axis, and upon which the recoiled cable is wound, and means whereby the rotation of the independent units may be relatively varied.

My invention also includes all the various novel features of construction and arrangement as hereinafter more definitely specified.

In the accompanying drawings, Figure 1 is a vertical longitudinal sectional view of a machine constructed in accordance with my invention; Fig. 2 is a transverse vertical sectional view of the machine shown in Fig. 1 taken on the line 2-2 in said figure; Fig. 3 is a transverse vertical sectional view of said machine taken on the line 3-3 in Fig. 1; Fig. 4 is a transverse vertical sectional view of said machine taken on the line 4-4 in Fig. 1; Fig. 5 is a side elevational view of a short length of the fabricated structure forming the shaft and showing the first layer of strands coiled upon the core; Fig. 6 is a side elevational view of a section of said shaft showing the second layer of strands coiled thereon; Fig. 7 is a side elevational view of a section of said shaft showing the third layer of strands coiled thereon; Fig. 8 is a vertical longitudinal sectional view of a machine embodying a slight modification of construction; Fig. 9 is a vertical longitudinal sectional view of a machine embodying another modification of construction; and Fig. 10 is a transverse vertical sectional view taken through the take-up reel on the line 10-10 in Fig. 9.

The machine shown in Figs. 1 to 4 inclusive may preferably be composed of separate units cooperatively connected and comprising a mandrel-dispensing or core payout carrier 1, the strand-feeding and winding or laying-on mechanism 2, the recoil or untwisting mechanism 3, arranged to rotate the cable about its longitudinal axis, and the take-up or spooling mechanism 4.

The core-dispensing carrier has the flier-frame 5 provided with trunnions 6 and 7 rotatably mounted in the standards 8 and 9 and having the mandrel or core-carrying spool 10, which is mounted to rotate in said flier-frame 5 on the shaft 11 whose axis extends transverse to the axis of rotation of said flier-frame 5, and which is arranged to pay out the mandrel or core 12 guided 10 through the hollow trunnion 7.

Rotation of the flier-frame 5 may be effected in any convenient manner, but I have chosen to illustrate a simple method which comprises the pulley 13 secured on the trunnion 6, and having varying diameters arranged to be connected by the belt 15 with a similar stepped pulley 16 on the counter-shaft 17.

The strand-feeding and winding mechanism comprises the strand bobbin frame having its end walls comprising the disks 20 and 21 connected by the spacing bars 22, and respectively having hollow trunnions 23 and 24 mounted for rotation in the standards 25 and 26, the trunnion 23 being extended inwardly to form the hollow stud 27 upon which the bobbins 30, 31, 32 and 33 may be rotatably mounted and removably held in position thereon by the disk 35, 30 which is retained on the stud 27 by the retaining nut 36.

Said bobbins 30, 31, 32 and 33 are respectively arranged to deliver strands 37, 38, 39 and 40 to the strand-twisting die 42, suitably mounted in the disk 21 and having therein suitable apertures 43 through which said strands are arranged to pass, and the aperture 44 for the core 12, which is directed through the hollow trunnion 23, hollow stud 27 and hollow trunnion 24, and about which said strands 37, 38, 39, and 40 are coiled by the rotation of the strand bobbin frame and its die 42. The strands 37, 38, 39 and 40 are respectively directed to the die 42 by passing over suitable guide rollers or pulleys 45, preferably carried by the spacing bars 22, and over the guide rollers or pulleys 46, which may be conveniently carried by the disk 35.

The rotation of the strand bobbin frame may be conveniently effected by the pulley 47 which is mounted on the trunnion 23 and connected by the driving-belt 49 with the pulley 50 on the counter-shaft 17, the pulley 50 being of much greater diameter than the pulley 47, so as to rotate the strand-bobbin frame at a comparatively high rate of speed.

As shown in Fig. 1, the stranded structure thus formed may be progressed longitudinally, at a predetermined rate of speed, by the recoil mechanism comprising the drum 52, around which said stranded structure may be wrapped for one or more turns, and which is mounted for rotation in the frame 53 on an axis transverse to the direction of

lineal movement of the stranded structure and having its peripheral surface in tangential relation with respect to the lineal axis of said stranded structure.

Said frame 53 is itself mounted for independent rotation about the axis of the stranded structure, having trunnions 55 and 56 mounted for rotation in the standards 57 and 58, and being provided with an aperture 59 forming a guide through said trunnions 55 and 56 for the passage of the stranded cable or shaft structure, which is arranged to be wrapped one or more turns around the surface of said drum, from which it passes to the take-up mechanism, to be hereinafter described.

The trunnion 55 of the recoil mechanism is provided with the stepped pulley 60, which is connected by the driving belt 61 with the stepped pulley 62 on the counter-shaft 17, and may be rotated with the core pay-out mechanism or may be rotated at relative speeds in the same or opposite direction as desired.

Positive rotation of the drum 52 on its axis may be effected through the worm gear 63 on the shaft 64 of said drum, by cooperation with the worm 65 whose shaft 66 carries the gear 67 in mesh with the gear 72 which is secured in stationary relation upon the standard 57.

The take-up mechanism comprises the take-up reel 75 having its shaft 76 mounted for rotation in the standards 77, and provided with the pulley 78 connected by the belt 79 with the pulley 80 on the counter-shaft 17. It will be obvious that said counter-shaft may be rotated in either direction, and the belts connecting the pulleys thereon may be either direct or crossed, depending upon the direction in which the various units of the machine are to be rotated, and said belts may so connect the pulleys as to vary the relative speeds at which the units may be actuated.

The various stages of construction of the fabricated rope or cable are depicted by enlarged illustrations in Figs. 5, 6 and 7; the first layer of strands 37, 38, 39 and 40, being laid side by side in coiled relation about the core or mandrel 12, as shown in Fig. 5; the second layer of strands being laid upon the first layer in oppositely directed coiled relation, as shown in Fig. 6; and the third layer of strands being coiled in crossed relation to the second layer, as shown in Fig. 7, whereby the composite cable or shaft is formed by layers of four strands disposed side by side, it being understood however, that the machine may be adapted to form the cable or shaft by fabricating the layers of one or more strands, and said cable or shaft may be formed of as many layers as may be deemed practical.

In the form of my invention shown in

Fig. 8, the longitudinal progression of the fabricated cable or shaft may be effected solely by the take-up mechanism, which may be so driven as to produce a predetermined constant pull to draw out said fabricated cable or shaft. Said take-up mechanism comprises the take-up reel 105, having its shaft 106 mounted for rotation in the standards 107, and provided with the pulley 108 connected by the belt 109 with the pulley 110 which is carried by a suitable slide frame 111 mounted for longitudinal movement on the counter-shaft 100, and having a friction wheel 112 arranged to alternately engage 15 the opposed surfaces of the friction disks 113 and 114.

The friction wheel 112 is arranged to be held in engagement with the friction disks 113 and 114 by the double bell-crank-lever 20 115, which has one arm engaged with the slide-frame 111 and its laterally extended arms 116 and 117 provided with suitable hooks 118 and 119 arranged to receive the loop or ring 120 of the weight 121. As will 25 be obvious, said weight may be engaged with either of said hooks 118 or 119, depending upon which of the friction disks 113 and 114 the friction wheel 112 is to be engaged, and upon the direction in which the counter- 30 shaft 100 may be rotated.

In this form of my invention shown in Fig. 8, the recoil drum 125, which is mounted for rotation in the frame 126 is rotated by the take-up mechanism pulling on the 35 fabricated cable, which is wrapped around said drum 125, as shown, and requires no gearing such as shown in Fig. 1. Furthermore, in Fig. 8 I have chosen to show the core dispensing bobbin and the recoil frame 40 so connected with the driving shaft as to rotate at relatively different speeds.

In the form of my invention shown in Figs. 9 and 10, the recoil or untwisting drum 130 is mounted for rotation about the axis 45 of its shaft 131 which is carried by bearings in the standard 132, said rotation being effected by the shaft being fabricated, which is wrapped one or more times around said drum and progressed by the takeup reel 135.

In this form of my invention, the takeup 50 reel 135 not only rotates on its axis to longitudinally progress the fabricated shaft, but it is also arranged to rotate bodily around the longitudinal axis of said fabricated shaft, said reel 135 having its shaft 136 mounted in suitable bearings in the frame 137, which has the trunnions 138 and 139 mounted to rotate in the standards 140 and 141, the former of which is provided 55 with the bore 142 through which the fabricated shaft passes to said takeup 135. The rotation of said frame 137 may be effected by the stepped pulley 143 which is connected by the belt 144 with the stepped pulley 145 60 on the countershaft 146.

The shaft 136 of the takeup reel 135, is arranged to be rotated by a train of gearing comprising the worm gear 147, worm 148, on the worm shaft 149 having the pinion 150 in toothed engagement with the gear 151, 70 which is secured on the standard 140, so, as will be obvious, when the frame 137 is rotated about the longitudinal axis of the fabricated shaft, the takeup reel 135 will be caused to rotate on the axis of its shaft 136. 75

It will be obvious that the takeup reel 135 and the worm gear 147 may both be secured to the shaft 136 so as to rotate the reel at a predetermined speed and consequently draw out the fabricated shaft at a like speed, or 80 said worm gear 147 may be loosely mounted to rotate on the shaft 136 and be frictionally connected with said shaft 136 and takeup reel 135 by any desired form of tension mechanism, such, for typical illustration, as 85 shown in Fig. 10, wherein the friction disk 152 is forced into engagement with the worm gear 147 by the spring 153 and the tension varied by the adjusting nut 154, whereby any desired pull may be exerted 90 to draw out said fabricated shaft.

Although, in this form of my invention, the recoil or untwisting drum 130 does not rotate bodily about the longitudinal axis of the fabricated shaft, as in the other forms 95 of my invention, it will be obvious, however, that said drum tends to cooperate with the takeup mechanism whose takeup reel 135 is arranged to rotate bodily about the longitudinal axis of the shaft being fabricated, to 100 effect a recoil or untwisting of the strands of said shaft.

It is to be understood that the means herein shown and described for actuating the associated mechanism is typical and simply 105 for illustrative purposes, as it is obvious that the parts may be readily connected for cooperation by other means, such, for instance, by suitably correlated gearing.

Furthermore, it is to be understood that 110 the core herein referred to may consist of a single strand or may be composed of a plurality of strands laid parallel, twisted together, or coiled about each other in any form desired.

My invention is advantageous in that the fabricated cable thus formed may be so rotated upon its longitudinal axis as to relieve the tension in the strands forming the layers during fabrication, so that when spooled 115 upon the take-up reel it will be substantially free from a tendency to twist upon itself and tangle, and when employed as shaft it will be substantially free from internal friction when rotated in flexed or curved condition. 120

I do not desire to limit my invention to the precise details of construction and arrangement as herein set forth, as it is obvious that various modifications may be 125 130

made therein without departing from the essential features of my invention as defined in the appended claims.

Having thus described my invention, I claim:

1. A machine of the class described, comprising rotary mechanism for fabricating a stranded shaft, means rotatable about the axis of said stranded shaft for spooling the shaft, and means interposed between said fabricating mechanism and spooling means arranged to prevent rotation of said fabricated shaft and thereby tend to relieve the inherent stresses therein before spooling.
2. A machine of the class described, comprising mechanism for fabricating a stranded shaft, means for spooling said fabricated shaft, means arranged to effect a recoiling or turning back of the coiled strands before spooling, and means tending to prevent the rotation of said fabricated shaft as it leaves the fabricating mechanism.
3. A machine of the class described, comprising mechanism arranged for fabricating a stranded shaft having a core, and having means for relatively twisting the core to create a predetermined inherent torsional stress therein during fabrication of said shaft.
4. A machine of the class described, comprising mechanism for fabricating a stranded shaft having a core, means for twisting the core to create a torsional stress therein during fabrication, and means for slightly recoiling or turning back the coiled strands wound on said core.
5. A machine of the class described, comprising mechanism for fabricating a stranded shaft having a core, means actuated in a predetermined sequence with the coiling mechanism for twisting the core to create a torsional stress therein during fabrication, and means actuated in a predetermined sequence with said coiling mechanism for recoiling or turning back the coiled strands wound on said core.
6. A machine of the class described, comprising a plurality of cooperative units including strand-twisting mechanism, and drawing-out mechanism arranged to rotate with respect to each other about the axis of the fabricated product.
7. A machine of the class described, comprising a plurality of cooperative units including core-dispensing mechanism, strand-feeding and winding mechanism, and drawing-out mechanism, all arranged to rotate with respect to each other about the axis of the core of the fabricated product.
8. A machine of the class described, comprising a plurality of cooperative units including means arranged to pay out a core strand, means arranged to wind strands about said core strand, and means arranged to progress the fabricated product longitudinally, all being mounted for relative rotation about the axis of said core strand, and cooperative to wind said strands together and to so recoil the fabricated product as to relieve the inherent tension.
9. A machine of the class described, comprising a plurality of cooperative units including means arranged to pay out a core strand, means arranged to wind strands about said core strand, and means arranged to progress the fabricated product longitudinally, all being mounted for relative rotation about the axis of said core strand, and cooperative to wind said strands together and to so recoil the fabricated product as to relieve the inherent tension, and means arranged to take up the fabricated product thus recoiled.
10. A machine of the class described, comprising a plurality of cooperative rotary units including core-dispensing mechanism, strand-feeding and winding mechanism, cooperative to form a fabricated shaft, take-up mechanism, and means disposed between the winding mechanism and take-up mechanism arranged to rotate the fabricated shaft upon its axis of longitudinal movement at a speed differing from the speed of rotation of said core dispensing mechanism.
11. In a machine of the class described, the combination with mechanism arranged to dispense a core, of mechanism arranged to wind a plurality of strands about said core, mechanism for progressing the fabricated product longitudinally, all being mounted to rotate about the axis of said core, means connected to contemporaneously rotate said mechanism, and means arranged to effect the relative rotation of said mechanism, and a take-up for the product thus formed.
12. In a machine of the class described, the combination with means arranged to dispense a core, of means arranged to form stranded convolutions about said core, means for progressing the fabricated product longitudinally and contemporaneously rotating said product about the axis of its core, and a take-up for the product thus formed; cooperative with said progressing means, to untwist said fabricated product.
13. In a machine of the class described, the combination with mechanism for feeding and twisting a plurality of strands together to form a stranded shaft, means rotatable about the longitudinal axis of the fabricated product, arranged to contemporaneously rotate said product about its axis while progressing it longitudinally.
14. In a machine of the class described, the combination with mechanism arranged to feed and twist together a plurality of strands to form a composite shaft having a core, means arranged to take up said shaft, and means interposed between said twisting

mechanism and said take-up means arranged to effect untwisting of said shaft whereby the strands are recoiled to relieve the internal friction between said strands, 5 and the core is twisted to produce torsion therein before fabrication.

15. Mechanism arranged to wind together a plurality of strands into a fabricated flexible shaft, and comprising strand-
10 winding means, takeup means rotatable about the longitudinal axis of said shaft, and means arranged to prevent the rotation of said shaft between said takeup means and said winding means, and thereby co-
15 operate with said takeup means to effect recoil or untwisting of said shaft.

16. Mechanism arranged to wind together a plurality of strands into a fabricated flexible shaft, and comprising strand-
20 winding means, take-up means rotatable

about the longitudinal axis of said shaft, and comprising a takeup reel, and a recoil or untwisting drum having a fixed axis of rotation, around which the said fabricated shaft passes to prevent the axial rotation of 25 said shaft between said takeup means and said winding means, and thereby cooperating with said takeup means to effect recoil-
ing or untwisting of said shaft to relieve inherent stresses. 30

17. The method of fabricating a composite shaft comprising a plurality of strands wound about a core, which consists in maintaining said core under torsional stress during fabrication of the wound strands, inde- 35 pendent of the natural stress incident to the winding of said strands thereon.

In witness whereof, I have hereunto set my hand this 17th day of July, A. D., 1924.

ROBERT C. ANGELL.
